(57) **CLAIM**

The ornamental design for the set of mounting lugs for a water filter, as shown and described.

DESCRIPTION

FIG. 1 is a top perspective of the two mounting lugs of this invention, each mounting lug having the same appearance; FIG. 2 is a front view of one of the mounting lugs of FIG. 1, with the back view being a mirror image thereof;

FIG. 3 is a left plan view of both of the mounting lugs of FIG. 1, with the right side view being a mirror image thereof;

FIG. 4 is a top plan view of the mounting lugs of FIG. 1; and, FIG. 5 is bottom perspective view of the mounting lugs of FIG. 1.

The broken line showing of portions of a water filter cartridge are for the purpose of illustrating environmental structure and form no part of the claimed design.
